UNITED STATES PATENT OFFICE.

JOHN C. DUPLER, OF MARIETTA, PENNSYLVANIA.

MOLDING-FLASK.

1,086,035.

Specification of Letters Patent.

Patented Feb. 3, 1914.

Application filed July 19, 1913. Serial No. 780,041.

To all whom it may concern:

Be it known that I, JOHN C. DUPLER, a citizen of the United States, residing at Marietta, in the county of Lancaster and State of Pennsylvania, have invented certain new and useful Improvements in Molding-Flasks, of which the following is a specification, reference being had to the accompanying drawings.

This invention relates to an improved apparatus for dumping sand out of the molding flask after the molded pattern has been removed therefrom, the object of the invention being to provide a simple and durable device of the above character wherein the sand in the molding flask may be quickly and readily dumped therefrom after the molded pattern has been removed from the sand.

Another object of the invention is the provision of an apparatus of this character which will possess advantages in points of efficiency and durability, is inexpensive of manufacture and at the same time is simple in construction and operation.

With the above and other objects in view, this invention consists in the novel features of construction and the combination and arrangement of parts to be hereinafter more fully described, pointed out in the claims and shown in the accompanying drawings, in which—

Figure 1 is a top plan view; Fig. 2 is a side elevation; Fig. 3 is a transverse sectional view.

Referring more particularly to the drawings, 1 indicates the frame of my improved flask having arranged transversely across the center a shaft 2, upon one end of which is mounted a gear 3, said gear being arranged upon the outer side of the frame 1. Mounted upon the stub shaft 4 and adapted to mesh with the gear 3 is a second gear 5, a handle member 6 being provided whereby the shaft 4 may be readily rotated to impart motion to the shaft 2. Extending longitudinally of the frame 1 are the spaced parallel plates 7, the ends of which are rigidly secured in any suitable manner to the ends of the frame 1. Arranged upon opposite sides and between the longitudinal plates 7 are the movable plates 8 which terminate short of the ends of the frame 1 and are mounted upon the shaft 2 for rotation therewith. The movable plates 8 are securely held upon the shaft 2 by means of the securing plates

9, which are arranged upon opposite sides of the plates 8 and rigidly secured to the shaft 2, thus securely holding the plates 8 against longitudinal movement upon the shaft. The ends of the shaft 2 are rotatably mounted within the side walls of the frame 1 and the intermediate portion of the shaft is mounted in suitable bearings formed in the longitudinal plates 7. Secured to each end of the frame 1 are the plates 10 which are provided with outwardly extending lugs 11 adapted to be engaged by a ring, hook, or other implement, carried by a derrick to raise the flask, when desired.

It will be readily apparent from the foregoing description taken in connection with the accompanying drawings that after the finished pattern has been removed from the sand in the mold, the flask is removed from the mold by means of a derrick or the like and the handle member 6 rotated to actuate the movable plates 8 to remove the sand from the flask. It will be readily understood that by actuating the movable plates 8, the sand which has become tightly packed within the flask may be quickly and readily removed therefrom. It will also be apparent from the description taken in connection with the accompanying drawings that my device is extremely simple in construction and can be manufactured at a comparatively low cost.

While I have shown and described the preferred form of my invention, it will be obvious that various changes in the details of construction and in the proportions may be resorted to for successfully carrying my invention into practice without sacrificing any of the novel features or departing from the scope of the appended claims.

As clearly illustrated in Fig. 2, I provide a pivoted pawl 12 which is adapted for engagement with the teeth on the gear 3 to prevent any rotary movement whatever on the part of the gear when the movable plates 8 are arranged in their operative position. It will be readily apparent that the pawl 12 may be quickly and easily raised and disengaged from the teeth on the gear 3 so that the gears 3 and 5 may be readily rotated.

What I claim is:—

1. A device of the class described including a frame, longitudinal plates connected to the end portions of said frame, a transverse shaft mounted for rotation within the frame, movable plates mounted upon said

2
shaft and adapted to be actuated thereby, a gear upon one end of said shaft, a second gear adapted to mesh with the first gear and a handle member carried by the second gear and adapted to actuate said shaft, as and for the purpose set forth.

2. A device of the class described including a frame, rigid plates arranged longitudinally therein and movable plates arranged

within said frame and in parallel relation 10 with the rigid plates, as and for the purpose set forth.

In testimony whereof I hereunto affix my signature in the presence of two witnesses.

JOHN C. DUPLER.

Witnesses:
